JET TURBINE BUCKET WHEEL

Robert G. Frank, Cincinnati, Ohio, assignor to the United States of America as represented by the Secretary of the Air Force

Filed Oct. 24, 1958, Ser. No. 769,524

1 Claim. (Cl. 253—77)

The present invention relates generally to buckets for use in jet turbines and as illustrated herein relates more particularly to turbine buckets of the type wherein air is circulated through the bucket for reducing the temperature thereof.

In jet engines and the like, an axial flow turbine operated by exhaust gases is usually provided which drives a blower for furnishing air under pressure to the burners. These turbines operate at very high temperatures and it is desirable to provide suitable means for reducing the temperature to a point where damage to turbine parts is reduced substantially.

It has, heretofore, been proposed to form axial flow turbine buckets with radial passages for the passage of a suitable cooling fluid. Such buckets, however, have been expensive, heavy and difficult to manufacture. One object of the present invention is to provide an inexpensive bucket which is relatively light and easily manufactured.

To this end and in accordance with one feature, the invention contemplates new and improved turbine buckets wherein high temperature, high strength alloy wire such as molybdenum could be attached as an integral part to either the hub or the rim of a turbine wheel in any suitable manner. Sheaths formed from oxidation resistant material are attached to the wires to form the airfoil surface. The light weight of this construction permits the use of a substantially lighter wheel. As illustrated, the high temperature, high strength alloy wires may be secured to either the rim or the hub of the turbine wheel by inserting the ends of the wires through openings, upsetting the ends of the wire and then brazing the upset ends to the wheel. This provides not only an effective method of anchoring the blades to the wheel but provides also a blade which is hollow and thus may readily be cooled. This enables the elimination of many of the problems associated with separate turbine components and permits operation at exhaust gas temperatures as high as 2600° F.

FIG. 3 is a view similar to FIG. 1 but showing additional means for supplying air to the airfoil body of the bucket;

5 FIG. 4 is a view similar to FIG. 1 but showing a different type of turbine wheel;

FIG. 5 is a fragmentary sectional view showing a thin solid wheel;

FIG. 6 is a transverse sectional view of any of the turbine buckets shown in FIGS. 1 to 5, inclusive;

10 FIG. 7 is a view, in section, showing the wires upset and brazed to the hub of the arrangements shown in FIGS. 1, 2 and 3;

15 FIG. 8 is a view, in section, showing a modification of the wheel shown in FIG. 3 wherein the bucket wires are upset and brazed to the inner ring;

FIG. 9 is a view, in section, showing the bucket wires upset and brazed to the outer ring; and

20 FIG. 10 is a fragmentary sectional view showing the bucket wires upset and brazed to the rim of the wheel shown in FIG. 4.

25 The drawings show turbine wheel designs of different types. The wheels shown in FIGS. 1, 2 and 3 disclose the bucket forming wires attached to the hubs of the wheels and, in FIGS. 4, 5, 7, 9 and 10, the bucket forming wires are attached to the rim of the wheel.

The design shown in FIG. 1 shows the bucket forming wires 10, attached to the hub 12 by upsetting and brazing the ends of the wires 10 after they have been inserted in holes formed in the hub 12. Spacer rings 14 are brazed 30 to the wires for rigidity and as a heat seal at the platform. As shown in FIG. 2, a shroud 18 may be brazed to the tip of the buckets 20 for the purpose of maintaining the shape thereof. Thin solid disks 16 are welded to the hub 12 and spacer rings 14 for torque conversion. 35 The hub 12 and the spacer rings 14 are suitably perforated to permit air cooling.

The wires 10 are formed of high temperature, high strength alloy. The wire and other parts of the turbine structure may be fabricated from molybdenum or plated 40 with an oxidation resistant material. Other high temperature high strength alloys may be used. Wires 10 preferably are formed from molybdenum or a molybdenum alloy which is sufficiently ductile to be drawn. Sheet metal and other shaped, cast or molded parts may be formed from other suitable alloys.

45 Suitable alloys include the following:

	Carbon (C)	Manganese (Mn)	Silicon (Si)	Chromium (Cr)	Nickel (Ni)	Cobalt (Co)	Molyb- denum (Mo)	Tung- sten (W)	Colum- bium (Cb)

With the above and other objects and features in view the invention will now be described with particular reference to the accompanying drawings in which:

FIG. 1 is a schematic view, partly in section, of a turbine bucket constructed according to the present invention;

FIG. 2 is a view similar to FIG. 1 but showing a different type of wheel structure;

65 It is to be noted that the wire receiving openings are arranged to form an airfoil surface of a type usual in turbine buckets for jet engines. The airfoil section of a turbine bucket 20 depicted in FIG. 6, shows clearly the spacing and positioning of the wires 10. It is evident that 70 closely spaced wires 10 form a relatively stiff shape about which a sheath 22 is wrapped. The inner surface of the sheath 22 and the wires 10 are coated with a suitable

brazing alloy and, after assembly, the sheath 22 and the wires 10 are welded together by any usual method. The outer surface of sheet 22 may be coated with an erosion and corrosion resistant material.

The construction shown in FIG. 3 is similar to that shown in FIG. 1 except that the sheath 22 of the bucket 20 shown in FIG. 3 extends down to the inner rings 14. In this construction the sheath 22 between the rings 14 could be formed of a lower temperature alloy material since it is not directly subjected to high temperatures to which the outer end portion of the sheath is subjected.

The wheel shown in FIG. 4 comprises a wheel fabricated from high strength alloy wire forming spokes 28 similar to a bicycle wheel fixed to the hub 12 and to the outer rim 30. The spokes 28 are covered by disks 32 which are also suitably fixed to the hub 12 and an inner ring 34.

The construction shown in FIG. 5 illustrates a solid forged wheel 38 on which are mounted turbine buckets similar to the ones shown in FIG. 4 and FIG. 10.

In FIGS. 7 to 10, inclusive, are disclosed various types of blade bases or supports to which the wires 10 are secured. The construction shown in FIG. 7 is substantially the same as the embodiment shown in FIG. 1 wherein the wires 10 are secured to the hub 12. FIG. 8 shows a construction similar to that shown in FIG. 2, but wherein the wires 10 are secured to the inner ring 14 instead of to the hub 12. The construction shown in FIG. 9 is similar to that shown in FIG. 8 except that the ends of the wires 10 are secured to the outer ring 14. The 30 FIG. 10 construction is substantially identical to that shown in FIG. 4 wherein the wires 10 are secured directly to the rim 30.

Regardless of how the wires 10 are secured to the

blade base or supporting structure the procedure followed in forming the sheath 20 about the blade is substantially the same. Brazing alloy may be applied directly to the wires by dipping, flame spraying or other suitable means as hereinbefore stated.

Having thus described my invention, what I claim as new and desire to secure by Letters Patent of the United States is:

A turbine bucket arrangement for jet engines comprising a bucket of airfoil cross section and a support structure for said bucket, said bucket comprising a series of contiguous wires of high strength, high temperature metal extending from said support and arranged in a single line to form a hollow bucket of said airfoil cross section, and a metal sheath conforming to said airfoil cross section and bonded continuously along the lengths of said wires conforming to said cross section, said support comprising a hub and an upstanding portion extending therefrom, said wires extending through said upstanding portion to said hub and means securing said wires to said hub.
